MECHANICAL BRAKING SYSTEM

Ernest D. Garrett, Shreveport, La., assignor of one-half to David G. Crow, Shreveport, La.

Application August 11, 1950, Serial No. 178,904

7 Claims. (Cl. 188—77)

My invention relates to mechanical braking systems generally, but more in particular to a mechanical braking system for use on heavy hoisting equipment such as might be found on the draw works of an oil well drilling rig.

In prior inventions of the present type, considerable effort has been put forth to produce a compact braking system for a drilling rig which would not only insure perfect control of the cable drum, but also be mechanically safe without attention or repair for considerable periods of time.

It is well known to those familiar with this type machinery, and more in particular the braking systems installed in oil well rigs, that the brakes must at all times be capable of stopping heavy loads suddenly and also making possible a payout of the line without jumping or seizing while the load is being handled. Since the brakes must support several thousand feet of pipe and cable, it is readily apparent that extreme care should be given to the design of the braking system so that the operator may stop the lowering or raising of the pipe string at a moments notice or signal and that within a minimum variation from a given stopping position. For example, when a joint of pipe is added to the upper end of a pipe string being lowered into the well hole, the driller must lower the string so that the upper threaded end is within reach of the workmen on the derrick floor for the addition of another joint. From constant practice and experience, the driller is able to lower the string in a matter of seconds and stop the upper threaded joint within a few inches of the same spot each time a joint is added. Should the brakes fail, it can be easily seen that not only will the entire string be dropped into the well hole, but the loose cable will endanger both men and equipment on the derrick floor.

When drilling, the entire pipe string is supported by the draw works of the rig and the weight of the pipe string is allowed to force the bottom bit into the earth. This lowering of the string must be slow and smooth so that the bit will not tend to dig into the formation or be wedged in rock and become damaged. In faulty brakes which usually allow a jerky movement when under a heavy load which is released slowly, it is apparent that a lower drilling bit is likely to become damaged.

Most of the mechanical braking systems arranged for use in drilling rigs consist of a pair of brake shoes partially encircling the outer ends of the cable drum and supplied with some leverage system finally connected to the main operating lever by which the brakes are applied. The arrangement of this leverage system as disclosed by the prior art has permitted the use of only 60 to 75 percent of the braking surface which has resulted in inefficient utilization of the braking drums, hence considerable wear on the brake shoes. The prior art does not disclose a system whereby the brakes are easily equalized when applied and released, nor does it show any arrangement by which one brake may be used to stop the drum rotation should a failure occur in the other.

2

It is apparent that these features incorporated into a braking system would be highly advantageous when applied to an oil field drilling rig.

It is an object, therefore, of the present invention to provide a braking system for an oil field drilling rig which is compact in its arrangement of parts and which may be readily adapted to any type or make of drilling rig.

Another object of the invention is to provide a braking system for oil field rigs which includes a means of equalizing the action of the brake shoes when the brakes are both applied and released.

A further object of the invention is to provide a brake system wherein the brake shoes substantially enclose the brake drum to permit a maximum braking action.

Still another object of the invention is to provide a pair of brake shoes operable by a single lever and wherein a single brake is used to stop the drum rotation should a failure occur in the other brake.

Another object of the invention is to provide a brake system wherein the ends of the brake bands substantially meet when encircling the brake drums and wherein the ends of said bands are pulled oppositely at substantially 180 degrees by members of the leverage system to apply the brakes.

A further object of the invention is to provide a braking system wherein the leverage of the system progressively increases the force applied to the brake as it is moved from the normal released position to the maximum applied position.

Further objects and advantages of the invention will become apparent in the course of the following detailed description when viewed together with the accompanying drawing in which:

Fig. 1 is an isometric view of a braking system for oil field drilling rigs made in accordance with the teachings of the present invention.

Fig. 2 is a broken side view taken along line 2—2 of Fig. 1.

In the drawing, and particularly in the view illustrated in Fig. 1, the device is shown as consisting of a pair of brake bands spaced in operative relationship with the ends of any conventional cable drum and supplied with identical leverage mechanisms finally connected together by an equalizing bar so that when the brakes are applied, each brake band, with its set of brake shoes will contact its portion of the cable drum simultaneously with the other to provide a smooth braking action. Since the leverage arrangement for each brake band is identical, reference is made in the following description to only a single "set" of parts constituting one complete brake assembly.

As above mentioned, each drilling rig is provided with a driven cable drum by means of which the string of pipe is raised or lowered into the well hole, the cable having one of its ends affixed to the drum and the other passing over a pulley in the derrick and supplied with adjustable slip jaws which grip the pipe string for lowering or raising. The drum itself is not shown in the drawing, but consists of a spool construction with the outer ends serving as brake drums which are encircled by the brake band 10 of the present invention. The brake band 10 is provided with several brake blocks or shoes 11 held to the band in spaced relationship by means of rivets 12, or the like. The two ends of the brake band are supplied with castings 13 and 14.

The upper casting 13, affixed to one end of the brake band 10, is provided with projecting lugs 15 having a common transverse hole 16 through the same. Into the spaces between the lugs 15, I have positioned the ends of a yoke arm 17 which is pivotally mounted to the casting 13 by means of a pivot pin 18 through the hole 16. The

yoke 17 is extended downwardly and converges into a cylindrical end 19 which is drilled and pinned to the yoke arms 20 of a knuckle joint member 21. The knuckle joint 21 is further pinned to a pivot plate 22 pivotally mounted between upwardly extended arms of a base casting 23. The base casting 23 is provided with feet 24 having holes 25 by means of which the casting may be bolted to the horizontally disposed bottom of the drum well (not shown).

The casting 14 on the other end of the brake band 10 is made similar to the one described above and also supplied with spaced projecting lugs 26 between two of which I have pivotally mounted one end of the brake actuating bar 27. It will be noted that this actuating bar 27 is arranged to receive a brake adjusting rod 28 which threadedly engages the upper end of the actuating bar 27 and is held in adjusted position by means of a lock nut 29. The upper end of the adjusting rod 28 also threadedly engages an upper yoke member 30 and is further secured in adjustment by another lock nut 31, as shown in Fig. 2. It will be understood that the threads on the ends of the adjusting rod are of opposite helix; so that, by turning the rod in a given direction, the diameter of the brake band 10 may be increased or decreased to effect a minimum of slack in the bands when they are in the released position. It will also be noted that the brake actuating bar 27 is extended upwardly between the lower yoke arms 17 and provided with a slight curvature not only for clearance purposes but also to permit the resultant forces, when the brakes are applied, to act in opposite directions substantially 180 degrees apart. This is highly desirable in a braking system since the friction between the drum and brake shoes, and, therefore, the actual brake horsepower, greatly increases as the coverage of the drums passes 50 to 60 percent of the total drum surface area. It is apparent, therefore, that if the brake bands and shoes of the present invention are active in engaging beyond 90 percent of the drum surface area, I have obtained maximum efficiency from a set of brakes, and have produced a braking system not heretofore known or used in the prior art.

The brake actuating mechanism is more clearly illustrated in Fig. 2 wherein is shown a supporting bracket 32 bolted to the vertical side wall 33 of the drum well and provided with upper and lower extending arms 34 and 35. The lower arm 35 is, in reality, a yoke which carries a bell crank 36 pivotally mounted between the arms of the same by means of a pin 37. One end of the bell crank 36 is pivotally attached to the yoke member 30 which is threadedly engaged with the brake adjusting rod 28. The other end of the bell crank 36 is provided with a slot 38 serving as a cam surface engaged by a cam which will be subsequently described.

The upper arm 34 is bored transversely and arranged to slidably receive a brake actuating rod 39 which is common to both sets of brake mechanisms as shown in Fig. 1. Affixed to this rod 39 by means of a key 40 and placed adjacent to the arm 34, I have provided lever 41 having a depending arm 42 which carries a cam 43 on its lower end arranged to ride in the cam slot 38 provided in the upper end of the bell crank 36. The upper end of the lever 41 is made into the form of a quadrant 44 which projects above the top plate 45 of the rig itself. The brake lever 46 may be of any desired shape and bent into a form suitable for actuation either by hand or the foot of the operator. The lower end of the brake lever 46 is formed into a yoke 47 which straddles the brake rod 39 and is made to lie adjacent the quadrant 44 of the lever 41. It will be noted that the quadrant 44 is supplied with several holes 48 by means of which the brake lever 46 may be secured in various raised or lowered positions for the convenience of an operator.

When the brakes are applied, that is, when the brake lever 46 is forced in the direction of the arrow in Fig. 2, the lever 41 and, consequently, the brake actuating rod

39 are partially rotated, bringing the lower clevis 36 into the position as shown by the dotted lines. It will be noted here that, in the released position, the center distance between the pin 37 and the cam 43 is comparatively short.

5 When the brakes are applied, however, this distance is increased since the lever 41 and bell crank 36 move in opposite arcuate directions. Thus the leverage is gradually increased from a normally released position to a maximum applied position.

10 The above description has been given to the several parts and movements of one assembly of the brake system. It is to be understood that the other set is made of identical parts having corresponding movements. As shown in Fig. 1, the common brake actuating rod 39 is extended across the upper edge of the drum well and affixed to a clevis (not shown), made similar to the lever 41 just described, but dispensing with the quadrant 44. The bands, shoes, and other levers are identical with those described above and are finally connected to their own pivot plate 22' pivotally mounted between the upwardly extended arms of its base casting 23'. Each pivot plate 22 and 22' is made substantially in the form of a triangle as shown in the drawing, with the inner corners arranged for pivotal attachment to a pair of yoke members 49 and 49'. The inner ends of a common stabilizing bar 50 which is further provided with lock nuts 51 and 51'.

15 Spaced more or less centrally between the base castings 23 and 23', I have provided a stop member 52 arranged to be affixed to the floor of the drum well and provided with a transverse bore slidably receiving the stabilizing bar 50. Mounted upon the stabilizing bar 50, upon each side of the stop 52, I have provided sleeves 53 and 54 held to the bar by means of set screws or the like. Encircling the bar 50, between the sleeves and the central stop 52, I have provided compression springs 55 and 56 which may be set to any amount of compression by moving and setting the sleeves.

20 It is now apparent that any movement of either of the pivot plates 22 or 22', in an effort to rotate about its mounting pin, will cause a corresponding movement to the other plate. If no force is exerted on either plate, then both plates will assume a neutral, balanced position due to the action of the compression springs 55 and 56. Such a construction is highly advantageous when applied to a 25 braking system in that the brakes are applied smoothly and evenly to the brake drums.

25 Each of the base castings 23 and 23' are supplied with a stop member 57 which, in reality is a web connecting the side arms of each base casting at the outer ends thereof, and serving as a stop member to limit the rotation of the pivot plates in either direction of rotation about their mounting pins. Thus, should failure occur in either set of brakes, such as by a sheared pivot pin, that particular pivot plate will be thrown against its stop 57 to prevent 30 further damage and to hold the opposite pivot plate while the brakes are applied.

35 The device is simple in construction and lends itself readily to any type drilling ring. While the component parts of the system are sufficiently strong for the purpose intended, they may be compactly arranged within a drum well and occupy a minimum of space. The stabilizing bar insures an even, simultaneous pressure applied to the brake drums and a simultaneous release of the shoes. The working height of the actuating brake lever 46 may be 40 quickly and easily adjusted to suit the operator and the 45 brakes may be set to an initial "tightness" by means of the brake adjusting rods 28.

45 The fact that the brake shoes cover approximately 90 percent of the braking surface of the drums cannot be over-emphasized. As before mentioned, the end castings 13 and 14 substantially meet at the band ends, the space left being allowed only for wear in the shoes. In the present instance, the main direction of the drum will be forward, that is, in a direction of rotation anti-clockwise in the view 50 illustrated in Fig. 1. Thus the greater thrust will be against

the bottom yokes 17 and against the base castings 23 and 23'. Since the two sets of brakes are equalized by means of the equalizing bar 50, they are made to engage simultaneously. Should the original brake setting be such that one brake engages the drum before the other, the action of the stabilizing bar will equalize any subsequent pressure applied by a rotation of the pivot plates 22 and 22'.

It is to be understood that the above illustration has been by way of example only and that changes could be made in the actual construction without departing from the scope of the invention as defined by the following claims.

I claim:

1. Apparatus of the class described comprising, a plurality of brake drums, brake bands extending respectively around said brake drums, lugs fixed respectively to the ends of said brake bands, yokes connected respectively to a lug on one end of each of said brake bands, a plurality of stationary base members, pivot plates pivotally mounted respectively in each of said base members and connected to said yokes, a stabilizing bar connected between said pivot plates, a stationary stop member provided with a bore slideably receiving said bar, sleeves adjustably fixed to said bar on opposite sides of said stop member, compression springs held respectively between each of said sleeves and said stop member, a rotatably mounted brake actuating rod, tension transmitting means extending substantially tangential to said brake bands respectively through said yokes and connecting the lugs on the other end of said brake bands to said brake actuating rod, and means for rotating said brake actuating rod.

2. Apparatus of the class described comprising a plurality of brake drums, brake bands extending respectively around said brake drums, lugs fixed respectively to the ends of said brake bands, yokes connected respectively to a lug on one end of each of said brake bands, a plurality of stationary base members, pivot plates pivotally mounted respectively in each of said base members, knuckle joints respectively connecting said pivot plates to said yokes, a stabilizing bar connected between said pivot plates, a stationary stop member provided with a bore slideably receiving said bar, sleeves adjustably fixed to said bar on opposite sides of said stop member, compression springs held respectively between each of said sleeves and said stop member, a rotatably mounted brake actuating rod, tension transmitting means extending substantially tangential to said brake bands respectively through said yokes and connecting the lugs on the other end of said brake bands to said brake actuating rod, and means for rotating said brake actuating rod.

3. Apparatus of the class described comprising, a plurality of brake drums, brake bands extending respectively around said brake drums, lugs fixed respectively to the ends of said brake bands, yokes connected respectively to a lug on one end of each of said brake bands, a plurality of stationary base members, pivot plates pivotally mounted respectively in each of said base members, knuckle joints respectively connecting said pivot plates to said yokes, a stabilizing bar connected between said pivot plates, a stationary stop member provided with a bore slideably receiving said bar, sleeves adjustably fixed to said bar on opposite sides of said stop member, compression springs held respectively between each of said sleeves and said stop member, a plurality of brake adjusting rods, tension transmitting means extending substantially tangential to said brake bands respectively through said yokes and connecting the lugs on the other end of said brake bands to said brake actuating rods, a rotatably mounted brake actuating rod connected to said brake adjusting rods, and means for rotating said brake actuating rod.

4. Apparatus of the class described comprising, a plurality of brake drums, brake bands extending respectively around said brake drums, lugs fixed respectively to the ends of said brake bands, yokes connected respectively to the

5 a lug on one end of each of said brake bands, a plurality of stationary base members, pivot plates pivotally mounted respectively in each of said base members, knuckle joints respectively connecting said pivot plates to said yokes, a stabilizing bar connected between said pivot plates, a stationary stop member provided with a bore slideably receiving said bar, sleeves adjustably fixed to said bar on opposite sides of said stop member, compression springs held respectively between each of said sleeves and said stop member, a plurality of brake adjusting rods, means extending respectively through said yokes and connecting the lugs on the other end of said brake bands to said brake adjusting rods, pivotally mounted bell cranks attached respectively to said brake adjusting rods, said bell cranks being provided with slots forming cam surfaces, a rotatably mounted brake actuating rod, levers mounted upon said brake actuating rod, said levers carrying pins arranged respectively for camming action against said cam surfaces, and means for rotating said brake actuating rod.

10 6. Apparatus of the class described comprising, a brake drum, a brake band extending substantially around said brake drum, lugs fixed respectively to the ends of said brake band, a yoke connected to a lug on one end of said brake band, a stationary base member, means connecting aid base member to said yoke, a pivotally mounted bell crank, means extending through said yoke and connecting a lug on the other end of said brake band to said bell crank, said bell crank being provided with a slot forming a cam surface, a rotatably mounted brake actuating rod, a lever mounted upon said brake actuating rod, said lever carrying a pin arranged for camming action against said cam surface, and means for rotating said brake actuating rod.

15 7. Apparatus of the class described comprising, a brake drum, a brake band extending substantially around said brake drum, lugs fixed respectively to the ends of said brake band, a yoke connected to a lug on one end of said brake band, a stationary base member, means connecting said base member to said yoke, a brake adjusting rod, means extending through said yoke and connecting a lug on the other end of said brake band to said brake adjusting rod, a pivotally mounted bell crank attached to said brake adjusting rod, said bell crank being provided with a slot forming a cam surface, a rotatably mounted brake actuating rod, a lever mounted upon said brake actuating rod, said lever carrying a pin arranged for camming action against said cam surface, and means for rotating said brake actuating rod.

20 8. Apparatus of the class described comprising, a brake drum, a brake band extending substantially around said brake drum, lugs fixed respectively to the ends of said brake band, a yoke connected to a lug on one end of said brake band, a stationary base member, a pivot plate pivotally mounted in said base member, means connecting said pivot plate to said yoke, a brake adjusting rod, means extending through said yoke and connecting a lug on the other end of said brake band to said brake adjusting rod, a pivotally mounted bell crank attached to said brake adjusting rod, said bell crank being provided with a slot forming a cam surface, a rotatably mounted brake actuating rod, a lever mounted upon said brake actuating rod, said lever carrying a pin arranged for camming action against said cam surface, and means for rotating said brake actuating rod.

25 9. Apparatus of the class described comprising, a brake drum, a brake band extending substantially around said brake drum, lugs fixed respectively to the ends of said brake band, a yoke connected to a lug on one end of said brake band, a stationary base member, a pivot plate pivotally mounted in said base member, means connecting said pivot plate to said yoke, a brake adjusting rod, means extending through said yoke and connecting a lug on the other end of said brake band to said brake adjusting rod, a pivotally mounted bell crank attached to said brake adjusting rod, said bell crank being provided with a slot forming a cam surface, a rotatably mounted brake actuating rod, a lever mounted upon said brake actuating rod, said lever carrying a pin arranged for camming action against said cam surface, and means for rotating said brake actuating rod.

30 10. Apparatus of the class described comprising, a brake drum, a brake band extending substantially around said brake drum, lugs fixed respectively to the ends of said brake band, a yoke connected to a lug on one end of said brake band, a stationary base member, a pivot plate pivotally mounted in said base member, means connecting said pivot plate to said yoke, a brake adjusting rod, means extending through said yoke and connecting a lug on the other end of said brake band to said brake adjusting rod, a pivotally mounted bell crank attached to said brake adjusting rod, said bell crank being provided with a slot forming a cam surface, a rotatably mounted brake actuating rod, a lever mounted upon said brake actuating rod, said lever carrying a pin arranged for camming action against said cam surface, and means for rotating said brake actuating rod.
